UNITED STATES PATENT OFFICE.

WILLIAM G. STOWELL AND LOVELL A. HERSH, OF DAYTON, OHIO, ASSIGNEES, BY
MESNE ASSIGNMENTS, TO HARRY BOHN, OF DAYTON, OHIO.

DESIGN FOR AN IRONING-MACHINE FRAME.

Application filed September 7, 1926. Serial No. 19,001. Term of patent 7 years.

To all whom it may concern:

Be it known that we, WILLIAM G. STOWELL and LOVELL A. HERSH, citizens of the United States, residing at Dayton, county of Montgomery, and State of Ohio, have invented a new, original, and ornamental Design for Ironing-Machine Frames, of which the following is a specification, reference being had to the accompanying drawings forming part thereof.

In the drawings Fig. 1 is a front elevation of an ironing machine frame showing our

new design; Fig. 2 is an elevation of the right hand end of such an ironing machine frame; Fig. 3 is a rear elevation of such an ironing machine frame; and Fig. 4 is an elevation of the left hand end of such a machine frame.

We claim:

The ornamental design for an ironing machine frame as shown.

WILLIAM G. STOWELL.
